ABSTRACT: The invention relates to a tape applicator for a tape of the type having one side of adhesive material and the other side of heat stable material. The applicator comprises a roller, heating means in the roller for heating the roller surface, and means for applying the heat stable surface of the tape upon the surface of the roller. The roller is mounted on an arm pivotally mounted in a frame which is slidably mounted. The roller rests upon a sheet supporting surface and a counterweight is connected to the arm for adjusting the pressure of the roller upon the sheet.

TAPE APPLICATOR

BACKGROUND OF THE INVENTION

1. Field of the Invention

The invention is in the field of tape structures, particularly those of weftless filament type, and of method and apparatus for adhesively applying such a tape to containers, packages, and the like.

2. Description of the Prior Art

Weftless filament tapes and their production are the subject of many prior art patents.

Tapes of various kinds are in widespread use as 1. reinforcement or closure means for containers, particularly those of paperboard or corrugated board type, wherein the tape is employed to retain closure flaps in closed position, and 2. as opening means for such containers, wherein the tape is appropriately positioned on the container and employed as a tear strip. Such tapes must possess adequate strength for the purpose and must also incorporate therein an adhesive layer to provide an effective bond to the container wall surface. It is, of course, desirable that, for practical use of such a tape, its cost of manufacture be as low as possible and that it be capable of application in a convenient and trouble-free manner. However, tapes of satisfactory strength are usually of such relatively high cost that their use is restricted to special circumstances. Moreover, the step of applying the tape is frequently attended by difficulties such as troublesome transfer of adhesive from the adhesive layer to surfaces of the applicator or the like.

SUMMARY OF THE INVENTION

An essential feature of the tape in accordance with the present invention is that it has a longitudinally extending surface coating section that has a surface contact adhesion characteristic at temperatures at which the remaining coating section is heat stable. Such surface contact adhesion characteristic is not of pressure sensitive type but rather requires the application of heat to render the surface coating section adhesive when applied to another surface.

Such a tape may be applied by an applicator having a heated surface arranged to soften only the one coating section whereby when such coating section of the tape is engaged with another surface the tape will be adhesively applied to such other surface.

The tape applicator of the present invention broadly comprises a roller, a heating element in the roller for heating the peripheral surface thereof, and means for directing a length of tape onto the peripheral surface of the roller.

The invention also resides in a method of applying the tape of the invention to sheet material which comprises applying heat to the heat-stable section of the tape for transmission through the tape to the adhesive section and softening thereof, and then applying the heat-softened section to the sheet material.

Brief Description of the Drawing

FIG. 1 is a cross section, on a greatly enlarged scale, of a tape in accordance with the invention,

FIG. 2 is a partial edge elevation of the tape of FIG. 1,

FIG. 3 is a cross section, also on an enlarged scale, of a modified form of tape,

FIG. 4 is a side elevation of a tape applying device, and

FIG. 5 is an end elevation, partly in section, of the device of FIG. 4.

DESCRIPTION OF THE PREFERRED EMBODIMENTS

Referring to FIGS. 1 and 2, 10 indicates a tape in accordance with the invention which comprises two layers 11 and 12.

Layer 11 comprises a plurality of elongated fibrous threads or strands or filaments 13. Filaments 13 extend longitudinally of the tape and may be of cotton, rayon, polyester, polyamide,

or other synthetic or natural fibers of strands. They are embedded in a synthetic resin material such as polymerized vinyl chloride, cellulose acetate, methyl methacrylate, polystyrene, and the like, which is stable at temperatures exceeding about 200° F., and below about -20° F.

Layer 12 consists of a hot-melt adhesive bonded adhesively to layer 11. Hot-melt adhesives are now recognized as a specific class of adhesives. They may comprise a low molecular weight natural or synthetic wax or resin, such as coumarone-indene resins; mineral, vegetable and petroleum waxes; alkyds; terpene and phenol-formaldehyde resins. This low molecular weight base material is reinforced and strengthened with a high molecular weight polymer such as ethyl cellulose, polyvinyl acetate, polyethylene, polystyrene, polyamide and the like. They are heat-stable at temperatures below about 150° F. and soften to an adhesive consistency at temperatures of about 250°-350° F.

Referring to FIG. 3, a strand of strip composed of rows of filaments 43 are arranged in tape configuration with the individual filaments in substantially directed contact with adjoining filaments.

A heat barrier coating or layer 44 is applied directly to one side surface of the strip, such coating being adhered directly to the filaments which become partially embedded therein. The coating may be composed of any suitable heat-stable composition, such as that employed in layer 11 of FIG. 1.

A hot-melt adhesive coating or layer 45 is applied directly to the other side surface of the strip, such coating being also adhered directly to the filaments which become partially embedded therein.

There is thus formed a tape having approximately half of its longitudinal surface extent constituted by one layer 44 and the other half of such longitudinal surface constituted by the layer 45.

Referring to FIGS. 4 and 5, the applicator shown comprises supporting frame generally indicated at 14 which may be mounted for adjustable sliding movement, by means of a guide 15, on a horizontal rail 16. As shown, adjustment may be effected by a rack 17 on the rail, a gear 18 meshing with the rack and fixed to a shaft 19 journaled in the guide and driven by a hand wheel 20.

A plate 21 fixed to the guide 15 has pivoted thereto at 22 an arm 23. Fixed to the free end portion of arm 23 is a spindle 24 on which is journaled a free-running roller 25. Roller 25 has a smooth peripheral surface 26 which is heated in any suitable manner. As shown, the heating means comprises an electrical resistance element 27 housed in a chamber 28 adjoining the peripheral wall 29. Power supply means for the element includes a cable 30 connected to a power source, a connector 31 having a pair of brushes 32 in contact with a pair of contact rings 33 carried by the roller hub 34, and connections (not shown) connecting the rings 33 with the resistance element.

The roller, through its peripheral surface 26, is arranged to rest upon a sheet 35 of corrugated board, paperboard or the like (for subsequent use as a container wall), such sheet 35 being disposed upon any suitable supporting surface 36. The sheet 35 is adapted to be moved along the surface 36 in any suitable manner in the direction of the arrow, such movement resulting in rotation of the roller 25. The pressure exerted by the roller on the sheet 35 may be adjustably controlled by means of an adjustable counterweight 37 mounted on a rod 38 fixed to arm 23.

A length of tape such as 10 is fed to the applicator from any suitable source of supply in such manner that a section thereof is in contact with a major portion of the peripheral surface 26 of the roller. As shown, the tape is fed over free-running rollers 39 and 40 mounted on brackets 41 and 42 carried by the frame 14 whereby it is fed onto an upwardly travelling portion of surface 26 and thence along the downwardly travelling portion of surface 26 until it comes into contact with the surface portion of sheet 35 upon which the roller rests. Thus, in the modification shown, the tape will be in contact with about three-quarters of the length of surface 26.

The tape 10 is fed onto roller surface 26 with the surface of layer 11 in contact therewith whereby the surface of layer 12 will be brought into contact with sheet 35. Surface 26 is heated by the heating means described to a degree only sufficient to render layer 12 adhesive and therefore without affecting the stability of layer 11. Ordinarily, the surface 26 will be heated to a temperature in the range of 200° F. to 400° F., for example, about 300° F.

It will be apparent, therefore, that on contact of the softened adhesive layer 12 with sheet 35, the tape 10 will adhere thereto. Moreover, movement of the sheet 35 as previously indicated will also act to provide a continuous feed of tape thereon.

Since the hot-melt adhesive layer 12 comes in contact with no surface of the applicator, there is no undesirable transfer of softened adhesive to parts thereof. In other words, heat transfer to the layer 12 is effected through the heat-stable layer 11. Moreover, the heat-stable layer 11 imparts to the tape a tensile strength that is at least several times that of a tape composed solely of a hot-melt adhesive.

It will be apparent that the diameter of roller 25 will be such that its circumference will have an extent chosen to provide a particular dwell time of the tape thereon, such dwell time being substantially only sufficient to render the layer 12 adhesively bondable to the sheet 35. An example of a satisfactory diameter is about 18 inches.

The tape of FIG. 3 may, of course, be applied by the applicator in the same manner as tape 10.

It will also be apparent that the dimensions of the tape will vary in accordance with its conditions of use. Obviously, its width may vary within wide limits. Its thickness will also be variable but an example of a satisfactory tape 10 for standard use is about 0.008 inch, layer 11 having a thickness of 0.005 inch and layer 12 having a thickness of 0.003 inch.

I claim:

1. A tape applicator comprising a supporting frame, an arm pivotally mounted in said frame, a roller rotatably mounted on said arm and having a tape engageable peripheral surface, a heating element in said roller for heating said surface, means for directing a length of tape onto said surface, a sheet-supporting surface, said roller having its peripheral surface resting upon said surface, and counterweight means connected to said arm for adjusting the pressure of said roller on said sheet-supporting surface.
2. A tape applicator as defined in claim 1, including a guide rail, a guide fixed to said frame and slidable along said rail, and means for adjusting the position of said frame and applicator on said rail.
3. A tape applicator as defined in claim 2, including tape guiding rollers mounted on said frame for guiding tape onto said peripheral surface.
